UNITED STATES PATENT OFFICE.

THOMAS W. LEONARD, OF DETROIT, MICHIGAN.

SELF-SHARPENING HORSESHOE.

SPECIFICATION forming part of Letters Patent No. 269,947, dated January 2, 1883.

Application filed August 2, 1882. (No model.)

To all whom it may concern:

Be it known that I, THOMAS W. LEONARD, of Detroit, in the county of Wayne and State of Michigan, have invented new and useful 5 Improvements in Self Sharpening Horseshoes; and I do hereby declare that the following is a full, clear, and exact description thereof, reference being had to the accompanying drawings, which form a part of this specification.

The nature of this invention relates to certain new and useful improvements in that class of horseshoes in which the heel and toe calks are so constructed as to become self-sharpening by wear; and the invention consists in the 15 peculiar construction and arrangement of parts, as hereinafter described and claimed.

Figure 1 is a bottom perspective of my improved shoe. Fig. 2 is an enlarged perspective view of the toe-calk detached, showing the manner of construction. Fig. 3 is an enlarged perspective view of a heel-calk detached.

In the accompanying drawings, which form 25 a part of this specification, A represents a horseshoe, the body of which is of the ordinary construction.

B represents the toe-calk, which is made of a thin piece of tempered steel re-enforced 30 upon each side by a piece of wrought-iron welded to the steel, during which action upon each end the said end is forged into a sharp lug, which enters the body of the shoe and is welded thereto when the calk is put in 35 place. The steel piece is lettered *a* and the re-enforcing pieces are lettered *b*. Otherwise in shape and manner of securing to the shoe the toe-calk is like those ordinarily employed.

C represents the heel-calk, which is made 40 of a piece of steel re-enforced on each side with a piece of wrought-iron, as already described in the toe-calk. The heel-calk is drawn down to a point, *c*. Ordinarily the heel of the shoe is drawn and bent at right angles 45 to the body to form the heel-calks; but in my construction this is not done, but a hole is punched into each of the heel ends of the shoe, and the point *c* of the heel-calk inserted and welded therein, as shown in Fig. 1, after 50 which the end *C* is drawn out and sharpened.

It will be understood that the hole for the shank *c* of the heel-calk does not extend entirely through the shoe, and that it is so welded as to become an integral part of the body.

A shoe thus constructed will not be required 55 to be taken off for the purpose of sharpening the calks, as in wear the softer iron will wear gradually, leaving the harder steel to protrude, thereby presenting the sharpened surface required, and this will continue until the calks are worn off close to the body of the shoe.

It must be understood that three strips or 60 pieces of metal—the two outer ones of wrought-iron and the intervening piece of steel—are welded together, and the pointed lugs *d* formed at the same time. This toe-calk is then properly welded to the body of the shoe, which is entirely of wrought-iron. The heel-calks 65 are formed in the same way and welded to the heel of the shoe, as described.

It will also be understood that the calks are 70 sharpened after they are in place upon the shoe, which can be readily done with a red heat, or a heat which will not interfere with the weld.

I am aware that the bodies of horseshoes 75 have been made of iron and steel welded together, as described in Patents Nos. 173,517 80 and 219,630. I am also aware that ordinary calks have been welded to the body of a wrought-metal shoe, as described in Patent No. 14,852. I am also aware that wedge-shaped teeth of steel, the largest ends fitting into a 85 groove in the calk, have been secured by striking the parts together by dies, as described in the Patent No. 246,505, and that a calk having a steel center, extending from end to end (without the lugs *d* in my device) has been secured to a shoe-body by screws, as shown by Patent No. 169,495; and also that a slot has been cut in the calk and a strip of much harder material inserted therein, as described in Patent No. 61,982; but in none of these cases do 90 I discover a calk of the construction mentioned secured to the body of a wrought-iron shoe by welding and the exposed calk subsequently sharpened. Hence I disclaim the construction mentioned.

What I claim as my invention is—
The horseshoe herein described, consisting of wrought-iron body A, and calks B C, formed of two outer strips or pieces of wrought metal, and an intervening piece of tempered steel welded together and having sharpened lugs d e, the said calks being welded to the

body of the shoe and subsequently sharpened, as set forth.

THOMAS W. LEONARD.
